UNITED STATES PATENT OFFICE.

FRANK A. DAVIDSON, OF BOSTON, MASSACHUSETTS, ASSIGNOR TO THE THEODORE METCALF COMPANY, OF PORTLAND, MAINE.

DESIGN FOR A CARTON-BLANK.

SPECIFICATION forming part of Design No. 29,644, dated November 8, 1898.

Application filed March 12, 1898. Serial No. 673,678. Term of patent 14 years.

To all whom it may concern:

Be it known that I, FRANK A. DAVIDSON, a citizen of the United States of America, and a resident of Boston, in the county of Suffolk 5 and State of Massachusetts, have invented a certain new and original Design for a Carton-Blank, of which the following is a specification.

Reference is had to the accompanying drawing, which is a plan view of the cardboard-blank from which the carton is made.

As shown in the drawing, the leading or material feature of my design consists in the peculiarly-shaped blank for a carton, the carton formed from the blank having the shape of a truncated rectangular pyramid.

One of the longer sides of the rectangular portion a' forms the longer parallel side of the trapezoidal portion a^4 , and the other of the 20 longer sides of the rectangular portion a' forms the longer parallel side of the trapezoidal portion a^2 . The non-parallel sides of the trapezoidal portion a^4 form each, respectively, one side of the two trapeziform-flaps a^{10} , and 25 the non-parallel sides of the trapezoidal por-

tion a^2 form each, respectively, one side of the two three-sided flaps a^9 . The shorter parallel side of the trapezoidal portion a^2 forms one of the longer sides of the rectangular portion a^5 . The other longer side of the rectangular portion a^5 is the longer parallel side of the trapezoidal portion a^6 , and the shorter sides of the rectangular portion a^5 are respectively the shorter parallel sides of the two trapezoidal portions a^3 . The longer parallel sides 35 of the trapezoidal portions a^3 are respectively the longer parallel sides of the flaps a^7 , the other two sides of which adjacent thereto are curved, as shown.

What I claim is—

The design for a carton-blank, as herein shown and described.

In testimony whereof I have signed my name to this specification, in the presence of two subscribing witnesses, on this 15th day of January, 1898.

FRANK A. DAVIDSON.
